UNITED STATES PATENT OFFICE

NOAH S. HARTER, OF WAUKEGAN, ILLINOIS

TRIANGULAR MESH FABRIC

Application filed May 16, 1928, Serial No. 278,303. Renewed October 23, 1929.

This invention relates to a new and improved chain-link wire fabric, and more particularly to a fabric of this character designed to resist deformation under strain lengthwise of the fabric.

Wire fabric of the chain-link type is in wide use and is manufactured by automatic machines in large quantities. This fabric as generally constructed consists of individual 10 wires or links extending substantially transversely of the fabric and interlinked with adjacent wires. As usually formed, the individual wires are in the shape of a flattened spiral. The portions of the individual wires 15 extend diagonally of the fabric alternately in opposite directions, each wire extending diagonally in one direction until it meets and is interlaced with an adjacent wire when it is reversely bent upon itself and extends 20 diagonally in the opposite direction until it meets and engages with the adjacent wire upon the other side.

This type of fabric when used for fencing is stretched when secured to the posts and, 25 due to the fact of its diamond-shaped mesh, it tends to elongate under strain and simultaneously to be reduced in width. The diamond-shaped mesh may have, when originally formed, axes transversely and longitudinally 30 of the fabric which are substantially equal. Under longitudinal strain the longitudinal axis increases in length and the transverse axis of the mesh correspondingly reduces in length. With ordinary type of fencing fabric 35 a strain of only a few hundred pounds may reduce the width of the fabric twenty per cent or more. This characteristic of the fabric makes it difficult to properly tighten and apply the fabric as a fencing, if its width is to 40 be maintained uniform and corresponding to the original width as woven.

It is an object of the present invention to provide a chain link fabric adapted to resist deformation under strain lengthwise of the 45 fabric.

It is an additional object to provide a fabric of this character in which portions of the wire links extend substantially longitudinally of the fabric.

50 It is a further object to provide a fabric

of this type having triangular mesh with adjacent links having their diagonal portions inclined in opposite directions.

It is an additional object to provide a fabric which may be commercially manufactured without material alteration in existing fence machines.

Other and further objects will appear as the description proceeds.

I have illustrated in the accompanying 60 drawings one preferred embodiment of my invention, in which

Fig. 1 is a face view of a fragment of the fabric constructed according to my invention; and

Fig. 2 is an edge view of the fabric.

In the drawings the link 11 has its end 12 twisted to lock with the end 13 of the link 14. The link 11 has the diagonally extending portions 15 and portions 16 extending substantially longitudinally of the fabric. The link 14 similarly has the diagonal portions 17 and substantially longitudinally extending portions 18. The diagonal portions 17 extend in opposite direction to the 70 diagonal portions 15 of the link 11. As clearly shown in the drawing, the links are interlaced so that their meeting angles are interconnected. These two links may be taken as characteristic of the entire fabric 80 and the adjacent links are similar in design. Each wire member therefore is provided with reversely bent portions, the wire or link 11 having such portions 15 and 16, and the wire 14 having the portions 17 and 18. It 85 will be apparent that the wire portions 16 and 18 extend in substantial alinement lengthwise of the fabric, while the alternate portions extend diagonally in opposite directions. As shown in Fig. 2, the fabric is not 90 entirely flattened but the diagonally extending portions are somewhat rounded as the links interlace.

In this type of fabric when a strain is put longitudinally of the fabric or substantially 95 in line with the link portions 16 and 18, this strain is resisted by these portions. There is, therefore, no material tendency for the fabric to be deformed and the shape of the meshes changed under such strain. Under test a 100

thirty-six inch wide section of this fabric has been found to have a reduction in width of approximately half an inch under a strain of five hundred pounds. The fabric is therefore well adapted for use where it must be installed under considerable strain or where it is desirable to maintain the width of the fabric substantially constant.

5 While I have shown one preferred form of my improved fabric, it is capable of modification and may be made in other forms, the essential features being that portions of the links extend substantially longitudinally of the fabric so as to directly take up strains 10 in that direction without material deformation of the fabric. I contemplate such changes and modifications as come within the spirit and scope of the appended claims.

I claim:

20 1. Chain link wire fabric consisting of interlocking wire members extending continuously across the fabric, said members each having alternate portions extending diagonally of the fabric and substantially lengthwise of the fabric, the lengthwise extending portions of one wire member being substantially aligned with those of adjacent wire members.

25 2. Chain link wire fabric consisting of interlocking wire members extending continuously across the fabric, said members each having alternate portions extending diagonally of the fabric and substantially lengthwise of the fabric, the diagonal portions of 30 adjacent members extending in opposite directions.

35 3. Chain link wire fabric consisting of interlocking wire members extending continuously across the fabric, said members each 40 having alternate portions extending diagonally of the fabric and substantially lengthwise of the fabric, the diagonal portions of adjacent members extending in opposite directions, the lengthwise extending portions 45 of one wire member being substantially aligned with those of adjacent wire members.

Signed at Waukegan, Illinois, this 11th day of May, 1928.

NOAH S. HARTER.
